SKI MECHANISM FOR AIRCRAFT OR OTHER VEHICLES

Harris S. Campbell, Willow Grove, Pa.

Application October 3, 1934, Serial No. 746,660

14 Claims. (Cl. 244—108)

The present invention relates to aircraft or other vehicles which may operate on snow or ice and particularly to the running gear therefor. One of the main objects of this invention is to provide an improved ski construction.

When an aircraft is to be operated from snow or ice it is customary to replace wheels with skis. It is an object of this invention to provide a ski mechanism which will permit a ready inter-10 change with wheel gear and will require a minimum amount of work and replacement of parts.

Many aircraft are provided with what is commonly known as a split undercarriage. Such an undercarriage usually has an individual 15 mounting for each wheel pivoted to the fuselage. A shock absorber strut extends from the vicinity of each wheel to a fixed point on the frame-work of the machine. Upon landing or taxiing, the shock absorber will move up or down permitting 20 the axle structure to assume different angular positions. It is common practice to remove these shock absorbers when skis are to be used on the machine in order that the movement of the landing mechanism with respect to the fuselage may 25 be eliminated. This is necessary with the usual type of ski which must be held rigid so that it will present a flat surface to the snow or ice at all times. If the shock absorber were not removed so as to provide a rigid structure, the ski 30 would ride on one edge or the other according to the position of the shock absorber, since a considerable width of the ski is in contact with the ice.

It is an object of this invention to provide a 35 ski mounting mechanism which may be used without removal of the shock absorber mechanism and which at the same time permits the ski to assume a proper position for travel through the snow regardless of the position of the axle 40 structure of the undercarriage. The necessity for making any alteration to the landing gear connecting structure is eliminated, thus simplifying the operation of changing from one type of operating gear to the other. The advantage 45 of retaining the shock absorber mechanism in the system while using the ski gear will be evident, particularly when the machine is to be operated over hard-packed snow or ice.

A further object is to eliminate certain of the 50 stresses which would be transmitted to the ski structure during some phases of operation, such as, for example on drift landing or running over uneven snow.

An additional object is to provide a ski construction which will permit landing with con-

siderable drift without digging in on one edge, but will actually offer resistance to the side drift and will tend to "climb" to the surface.

These objects are accomplished by the use of a special pivotal mounting for connecting the ski to its framework. The pivotal axis is arranged longitudinally on the ski. The actual axis in the preferred form of the invention is located below the contact surface of the ski. Thus, instead of a complete circular pivot, the bearing which mounts the ski to its frame takes the form of an arc of a circle of sufficient length to permit movement through the range of angles required in operation. This unique arrangement eliminates any tendency for the ski to dig in when there is a side component of movement, either because of landing with drift or because of angular movement of the undercarriage axle. In contrast, the mechanism provides a stable moment which causes the ski to assume a positive angle 20 with respect to the surface when any side movement is present. When operating on snow this is of great advantage. Of course the pivotal mounting also permits the ski to lie flat for all angular positions of the axle mechanism when 25 operating on hard packed snow or ice.

A further object is to provide a ski structure which can be placed upon the wheel axle and readily secured in position by the same parts used to retain the wheel.

Another object is to provide effective and compact mechanism for maintaining the ski in the most efficient position on its transverse axis (normally the axle of the wheel) during flight, but allowing the ski to assume readily the various 35 positions which may be required in landing. This latter object is accomplished in a simple manner by mounting the necessary stops and springs upon the flange which carries the brake when wheel gear is used.

How these and other objects incident to the invention are obtained will be clear from the following description together with the drawings in which—

Fig. 1 is a side view of an aircraft having a landing gear incorporating the present invention.

Fig. 2 is a front view of the same aircraft.

Fig. 3 is a front sectional view of a typical wheel mounting.

Fig. 4 is an enlarged front view of one side of 50 the landing gear showing the members and ski mounting.

Fig. 5 is an enlarged front view of the ski structure and mounting partly in section, taken along the line 5—5 of Fig. 6.

Fig. 6 is a side view partly in section, taken on line 6-6 of Fig. 5.

Fig. 7 is a front sectional view of an alternative method of connecting the ski to its mounting structure, taken along line 7-7, Fig. 8.

Fig. 8 is a section taken along line 8-8 of Fig. 7.

The craft shown in Figs. 1 and 2 consists of fuselage 10 having occupants' compartment 11. Wings 12 support the machine during flight and engine 13 and propeller 14 supply the means for propulsion. The usual control surfaces are shown, ailerons 15, vertical tail surfaces 16 and horizontal tail surfaces 17. The main wings 12 are braced by means of struts 18 and 19.

The landing gear, indicated generally at 20, is made up of V-axle members, the front member 21 of V being shown in Fig. 2 and the rear member 22 in Fig. 1. A normal shock absorbing strut 23 completes the tripod structure of the landing gear. This is attached pivotally at its lower end 24 and also by pivot 25 at its upper end to strut 18. This point is supported by brace 26. V struts 21 and 22 are also pivoted to the fuselage at 27.

For normal operation the landing gear is provided with a wheel 28 shown by dotted lines in Fig. 1, and Fig. 2. The wheel (shown in greater detail in Fig. 3) is mounted for rotation on stub axle 29. A brake flange 30 is provided on axle 29 to anchor the wheel brake 31 to the axle by means of bolts 32.

In order to remove the wheel 28 the retaining collar 33 is taken off by withdrawing bolt 34 (shown also in Fig. 5). The complete wheel assembly including brake drum 35 and bearings 36 may then be withdrawn from the stub axle 29. After the wheel has been removed, the brake assembly 31 can be dismounted by removing bolts 40 32.

By reference to Figs. 5 and 6, it will readily be seen how the ski assembly is attached to the axle 29. The structure to which the ski itself is mounted consists of sleeve 37 with supporting struts 38 running angularly downwardly to fittings 39. A tie tube 40 connects the fittings 39. To mount the ski assembly on the aircraft, the sleeve 37 is slid over axle 29 and the retaining collar 33 is replaced. Welded or otherwise fastened to sleeve 37, there is a plate 41 embodying arm 42. A plate 43 of somewhat similar shape and having arm 44 is attached to the brake flange 30 by using some of bolts 32 which hold the brake assembly in place when wheel landing gear is used.

A compact tension spring 45 connects arms 42 and 44 and a resilient member such as rubber block 46 is inserted between bracket plates 47 and 48, located on plates 41 and 43. The spring 45 maintains the ski 49 in substantially horizontal position during flight as shown in full line position, Fig. 1. Upon landing the spring 45 stretches to permit sleeve 37 to rotate on axle 29, so that the ski may assume a position such as 49a (Fig. 1). In flight the rubber block 46 is under compression due to the action of spring 45. The rubber block 46 allows the ski to take up a position above horizontal in case of necessity, such as in a tail high landing upon an uneven surface. The edges 50 and 51 of plates 41 and 43 are arranged so as to provide adequate clearance for the necessary movements of the ski and at the same time these edges provide a stop to prevent excessive angular movement such as

might occur in flight in case of failure of spring 45.

Some of the chief features of the present invention are embodied in the method of mounting the ski upon the supporting structure. In order to distribute the load evenly over the width of the ski shoe 49, brackets 52 are bolted thereto. So that the ski 49 may assume different angular positions with respect to its supporting structure 38, etc., a longitudinal pivotal connection is used between the fittings 39 and bracket 52. In the preferred form of the invention, the actual longitudinal axis 53 about which the ski may oscillate is located below the bottom surface of ski 49. The moving connection takes the form of a slot 54 having curved surfaces 55 and 56 and formed in the central portion of bracket 52. The surfaces 55 and 56 are arcs of circles having their centers at point 53. A block 57 is shaped to fit inside the slot 54 and is securely fastened by bolts 58 to the fitting 39. Sufficient clearance is left between the ends of block 57 and slot 54 to permit the angular movement of the ski required in operation. A small spring 59 is shown in Fig. 5 which tends to urge the ski so that in flight it will assume a substantially level attitude, (as shown in chain dotted position 49b, Fig. 4). In Fig. 4, the full lines indicate the position of the ski and landing gear members while at rest on the ground. The chain dotted lines 49b, 21b indicate the position assumed during flight or at the instant of contact with the ground before the weight has been transmitted to the structure, the shock strut 23b being in extended position. The dotted lines 49c, 21c show the landing gear in its full up position, such as upon a landing, the shock absorber strut 23c being fully compressed. Although the strut 21 and axle 37 change their angular position as they rotate about pivot 27, it should be noted that the bottom surface of ski 49 can always maintain complete contact with the surface of the snow or ice.

In moving from position 49b to position 49c (Fig. 4) it will be seen that besides an upward travel there is also a considerable side component of movement. The action of the ski under these conditions can best be described with reference to Fig. 5. When there is movement of the ski in the direction of arrow 60 the resistance of the snow causes a force to act at the edge of the ski 49—indicated by small arrow 61. This force 61 acting above the longitudinal rotational axis 53 causes the ski to turn slightly in the direction of arrow 62 with the result that the ski bottom 55 assumes a positive angle with respect to the snow surface, thus eliminating any tendency of the ski to dig into the snow. Also in this fashion the ski mechanism is able to operate without difficulty when a landing is made in soft snow 60 with considerable side drift.

Figs. 7 and 8 illustrate a joint having the same general features as that shown in Figs. 5 and 6, but different as to details of construction. In bracket 62, there is an opening 63, having its top and bottom formed from arcs of circles with centers at point 53. A fitting 64 is connected with struts 38 and straddles bracket 62. In fitting 64 provision is made for carrying two large rollers 65 by means of small roller bearings 66 which are housed in bosses 67 of fitting 64. This forms a connection in which the frictional resistance is very low since when angular movement occurs between fitting 64 and bracket 62, rollers 65 roll on the surface of the slot or open- 75

ing 63. Of course there is a slight clearance, the diameter of the roller 65 being slightly less than the width of the slot 63, so that the unloaded side of the roller will be clear when the load is applied. Centralizing springs 68 may be used to maintain a substantially central position of the ski during flight. These springs are attached to the fitting 64 and to clips 69 held by bolts 70.

From the foregoing description it will be evident that a number of advantages may be derived from this improved ski construction. The simple and compact mechanism for mounting the ski on the wheel axle permits ready changing from one type of landing gear to the other. By mounting the ski on a longitudinal axis, particularly of the type indicated, the safety of the aircraft is increased, especially when landing on a rough and uneven surface or with side drift. The longitudinal pivotal mounting also permits retaining the shock absorber mechanism for use with ski gear, thus providing greater comfort to the occupants as well as reducing the shocks transmitted to the frame and joints of the machine with consequent reduction in servicing requirements. Because of its ability to adapt itself to uneven surfaces, the ski structure stands up well under rigorous operating conditions since the flexing strains are largely obviated, not only in the ski shoe, but also in the mounting members.

It is not intended that the present invention be restricted to the specific structures shown and described, but only by the scope of the appended claims.

I claim:—

1. For an aircraft, a landing gear having an axle member normally carrying a wheel for rotation thereon, a ski structure capable of replacing said wheel, said structure consisting of an upper axis member to mount the ski upon the axle and arranged to permit a limited angular movement thereon, a ski shoe having an elongated plan form, a supporting means interconnecting said ski shoe and said upper axis member, a pivotal connection between the ski shoe and the supporting means, said pivotal connection having an axis which lies longitudinally of the ski shoe and substantially perpendicular to the said upper axis member, said axis being located below the plane of said ski shoe.

2. For an aircraft, a landing gear having an axle member normally carrying a wheel for rotation thereon, a ski structure capable of replacing said wheel, said structure consisting of an upper axis member to mount the ski upon the axle and arranged to permit a limited angular movement thereon, a ski shoe having an elongated plan form, a supporting means interconnecting said ski shoe and said upper axis member, a pivotal connection between the ski shoe and the supporting means, said pivotal connection having an axis which lies longitudinally of the ski shoe and substantially perpendicular to the said upper axis member, said pivotal axis further being located below a plane passing through the longitudinal edges of said ski shoe so that a horizontal pressure upon an edge of said ski shoe causes angular movement of the shoe in a direction which raises the edge of the shoe upon which the pressure is applied.

3. For an aircraft, a landing gear having an axle member normally carrying a wheel for rotation thereon, a ski structure capable of replacing said wheel, said structure consisting of an

upper axis member to mount the ski upon the axle and arranged to permit a limited angular movement thereon, a ski shoe having an elongated plan form, a supporting means interconnecting said ski shoe and said upper axis member, a connection allowing the ski shoe to assume various angular positions with respect to said supporting means, said connection having a longitudinal axis located sufficiently below the plane of the ski shoe that a lateral movement of the ski causes the ski shoe to tend to assume a positive angle with respect to the direction of said lateral movement.

4. For a running gear capable of use on snow or ice, an axle structure, a ski mechanism mounted on said axle structure for limited angular movement thereon, a supporting means extending downwardly from said axle structure, a ski shoe having an elongated plan form, a connection between said supporting means and said ski shoe arranged to permit angular movement of the ski shoe with respect to said supporting means, the angular movement being about a longitudinal axis located below the plane of said ski shoe.

5. For a running gear capable of use on snow or ice, an individually sprung axle structure, a ski mechanism mounted on said axle structure for limited angular movement thereon, a supporting means extending downwardly from said axle structure, a ski shoe having an elongated plan form, a connection between said supporting means and said ski shoe arranged to permit angular movement of the ski shoe with respect to said supporting means, the angular movement being about a longitudinal axis located sufficiently below the plane of said ski shoe that a horizontal pressure at the edge of said ski shoe produces a turning moment about said axis tending to raise the edge of the ski shoe to which the pressure is applied.

6. For a running gear capable of use on snow or ice, an axle structure, a ski mechanism mounted on said axle structure for limited angular movement thereon, a supporting means extending downwardly from said axle structure, a ski shoe having an elongated plan form, a connection between said supporting means and said ski shoe arranged to permit angular movement of the ski shoe with respect to said supporting means, the angular movement being about a longitudinal axis located below a plane passing through the longitudinal edges of said ski shoe so that a side component of movement causes said ski shoe to tend to rotate about said axis in a manner such that the edge of the ski toward the direction of movement is raised.

7. In an aircraft, an axle member, a ski structure having a tubular member for mounting the ski upon said axle member, a pair of struts attached to said tubular member at spaced points and converging downwardly and forwardly, a second pair of struts attached to said tubular member and converging downwardly and rearwardly, a fitting attached to each pair of struts at their lower ends, a ski shoe having brackets attached thereto, said brackets being arranged to co-operate with said fittings to provide for relative motion between said ski shoe and said struts about a pivotal axis disposed longitudinally of the ski and below the plane of the ski shoe.

8. In a ski construction, a ski shoe, a supporting structure, a connection between said ski shoe and said structure comprising a fitting

- 5 permitting relative angular movement of the ski shoe with respect to the supporting structure, an axis about which the ski shoe rotates, said axis being located below the general plane of the ski shoe so that an edge of the ski shoe tends to raise in response to a horizontal pressure applied at that edge.
9. In a ski construction, a ski shoe, a supporting structure, a connection between said ski shoe and said structure providing for relative movement therebetween about a longitudinal axis, located slightly below the bottom surface of said ski shoe, said connection incorporating a fitting having an arc shaped slot whose center lies on said axis.
10. In a ski construction, a ski shoe, a supporting structure, a connection between said ski shoe and said structure providing for relative movement therebetween about a longitudinal axis, located slightly below the bottom surface of said ski shoe, said connection incorporating a fitting having an arc shaped slot whose center lies on said axis, said fitting being mounted on said ski shoe, and sliding block means shaped to fit 15 said slot and connected to said structure.
11. In a ski construction, a ski shoe, a supporting structure, a connection between said ski shoe and said structure providing for relative movement therebetween about a longitudinal axis, located slightly below the bottom surface of said ski shoe, said connection incorporating a fitting having an arc shaped slot whose center lies on said axis, said fitting being mounted on said ski shoe, and rolling means connected to said 20 structure and adapted to roll in said slot.
12. In an aircraft, a ski structure for use with an undercarriage of the split axle type, said ski structure having a ski shoe and supporting members, said ski shoe being mounted for relative 25 movement with respect to said members by means of a pivotal connection having an axis longitudinally disposed below the general plane of the ski shoe and arranged to permit an edge of the ski shoe to raise in response to a horizontal pressure applied at that edge, and a single spring means urging the ski shoe to one extreme of its angular movement so that the ski shoe assumes a substantially horizontal position when the undercarriage is extended during flight.
13. For an aircraft, a landing gear having a pair of individually mounted axle structures, each of said axle structures being pivotally connected to the frame of the aircraft, a shock absorbing unit connected to said axle structure in such a manner that upon deflection of the shock absorbing unit the axle structure moves on its pivotal connection, ski mechanism mounted upon said axle structure and composed of a ski shoe and supporting structure, means incorporated in said ski mechanism for allowing its use with said pivotally connected axle structure and shock absorber unit, said means involving a connection between said ski shoe and said supporting structure providing for relative movement therebetween about a longitudinal axis located below the general plane of the ski shoe.
14. A ski construction for a vehicle including an elongated ski shoe and a mounting structure therefor, a connection between said ski shoe and said mounting structure arranged to permit relative angular movement therebetween, said connection providing a longitudinal axis about which the ski shoe rotates, said axis being located below a plane through the edges of said ski shoe.

HARRIS S. CAMPBELL.
